UNITED STATES PATENT OFFICE.

PHELPS BROWN, OF SPRINGFIELD, MASSACHUSETTS.

ARMATURE-ACTUATING MECHANISM.

Application filed March 24, 1926. Serial No. 97,011.

This invention relates to improved mechanism for actuating the armature of a magneto.

The invention is an improvement on that of U. S. Patent No. 1,517,948, granted December 2, 1924, on an invention of Phelps Brown and Ira E. Hendrickson. Like that invention the present one contemplates driving mechanism of a type wherein the 10 armature may be initially moved out of contact with its magnetic poles by an inelastic transmission of force from the drive shaft, immediately followed up by a transmission of force from previously stressed elastic 15 means; or wherein the armature may be driven entirely by the described inelastic transmission of force. The first plan of operation is useful on starting or low engine speeds and the latter for higher engine 20 speeds. In shifting from the first to the second plan of operation, the desired advance in speed is automatically obtained.

The object of this invention is to provide an improved armature actuating mechanism 25 for the general purpose, above set forth, and to provide such a mechanism which is more convenient to operate, cheaper to manufacture and assemble, and simpler and more compact in form.

30 Other objects and advantages will appear in the following description and will be pointed out in the appended claims.

The invention will be disclosed with reference to the accompanying drawings, in 35 which:—

Fig. 1 is a front elevational view of a magneto embodying the armature actuating mechanism of this invention;

Fig. 2 is a bottom plan view taken on the 40 line 2—2 of Fig. 1;

Fig. 3 is an enlarged but fragmentary view, taken similarly to Fig. 2, but showing the armature actuating mechanism shifted into position for direct drive;

45 Fig. 4 is an enlarged cross sectional view taken on the line 4—4 of Fig. 1;

Figs. 5 and 6 are enlarged but fragmentary cross sectional views taken on the lines 5—5 and 6—6, respectively of Fig. 1;

50 Fig. 7 is a fragmentary rear elevational view illustrative of the devices for shifting the armature actuating mechanism;

Fig. 8 is a sectional plan view taken on the line 8—8 of Fig. 7;

55 Fig. 9 is a sectional elevational view taken on the line 9—9 of Fig. 4;

Fig. 10 is an enlarged sectional view illustrative of the mounting of the lever arms of the armature actuating mechanism; and

Figs. 11 and 12 are plan and elevational 60 views, respectively, of one of such lever arms.

The present invention, being directed primarily to mechanism for actuating the armature, is largely independent of the particular details of construction of the other parts of the magneto. The magneto shown is illustrative of a general type and is one example of many various magnetos of this general type with which the invention may be used.

The magneto illustrated is, with the exception of the armature actuating mechanism and the armature mounting, constructed in the manner fully disclosed in United States Letters Patent No. 1,557,976, granted October 20, 1925, on an invention of Phelps 70 Brown and Terrence G. Louis and reference is made to this patent for a more complete disclosure of the general construction of the magneto.

The frame A of the magneto is essentially 80 like that of said patent except that it is extended to one side to provide for the mounting of the armature actuating mechanism and except that it is provided with supporting legs 10, which support it from a lower housing exemplified in part by the bed 11. The magnets 12, cores 13, primary coils 14 and secondary coils 15 are supported from frame A in the same manner shown in said patent,—the lower ends of the cores being 85 clamped between the frame proper and a separate frame member 16 by bolts 17. The interrupter casing 19 is fixed in frame member 16 (Fig. 6) and carries a fixed breaker point 20 insulated from the casing. The latter also slidably receives a plunger 21

which carries the movable breaker point 22 and has a stem 23 extending loosely through a lug 24 fixed to the armature 25. A spring 26 acts between lug 24 and the base of 90 plunger 21 to lift the latter, whenever possible, and hold the breaker points 20 and 22 in engagement. These points are separated when an abutment 27 on stem 23 is engaged and moved by the under side of lug 24. A 95

second abutment 28 is provided below abutment 27 to permit operation of the breaker points by other mechanism, as will herein-after appear. The electrical and magnetic 100 circuits are, or may be, like those shown in the patent above referred to.

The armature 25 is pivotally mounted to

swing toward and into contact with the lower ends of cores 13 and away from the same, thereby effecting a variation of flux in the magnetic circuit in a known manner. This 5 pivotal mounting is effected by fixing the armature to a shaft 30 (Fig. 2) which is rotatably mounted in two spaced lugs 31 formed as integral parts of frame A and disposed near the back edge thereof. A 10 pair of armature return springs 32 (Fig. 1) act between the bed 11 and armature 25 with a tendency to lift the latter toward and into contact with cores 13. The armature is fixed to shaft 30 by cap screws 33 15 (Figs. 2 and 6) which each pass freely through lug 24, the laminations of armature 25, a sleeve 34 and one ear of a split collar 35, which encompasses shaft 30. The cap screws are threaded at their extremities into 20 the other ears of collars 35. Consequently, these screws act to hold the lug 24 to armature 25; to clamp the armature laminations together; to hold the armature to the split collars 35 and to tighten the ears of 25 the collars so that they securely grip shaft 30. An operating arm 36 is suitably fixed to shaft 30, at a location underlying the lateral extension of frame A by means of which arm the shaft may be turned to operate 30 the armature. Arm 36 has a surface 37 and carries a stud 38,--these parts 37 and 38 forming abutments movable with the armature. One or the other of these abutments is engaged by the armature actuating 35 mechanism according to whether the armature is to be driven in its flight away from the poles entirely by an inelastic transmission of force or by the expansive effort of a previously stressed elastic means following 40 the breaking of the magnetic hold on the armature by an inelastic transmission of force.

The armature actuating mechanism includes a unit which is mounted on shaft 30 45 adjacent arm 36 for swinging movement and which is also mounted to freely slide in an axial direction on this shaft from one position to another to effect the two kinds of armature movement just described. This 50 unit comprises two levers 40 and 41 which are, or may be, exact counterparts. One of these levers is shown in detail in Figs. 11 and 12 and, as will be seen from these figures, the lever may be advantageously made 55 from sheet metal by punch press operations at low unit cost. Two of these levers are selected, arranged reversely, and then placed side by side in contiguous relation. When thus arranged, they are mounted on a common hub 42 (Fig. 10) which in turn is slidably mounted on shaft 30. The levers are held against relative axial displacement on the hub between a flange 43 and the crimped over end 44 of hub 42. The flange 43, in 60 cooperation with a similar flange 45 on hub

42, affords a clutch collar having a peripheral groove 46. The lever 40 has an outwardly turned lug 47 which underlies lever 41 and the latter has a similar lug 48 which overlies the lever 40 (Figs. 4 and 5). These 70 lugs 47 and 48 limit the extent to which the levers can move away from one another. The free ends of the levers 40 and 41 are bent in reverse directions (Fig. 3) and have projections 49 and 50 (Figs. 4 and 5), respectively, which by reason of the bending of the levers, are so positioned that part of one projection will overlie part of the other projection. Consequently, these projections serve as abutments which will engage and 80 limit the extent to which the levers may be moved toward one another. An armature drive spring 51, in the shape of a coil spring, is interposed between the free ends of the levers 40 and 41, the projections 49 and 50 85 being of a size to enter within the coils of the spring and hold the same in place. The lever 40 has an integral lug 52 which is turned outwardly and adapted, when the unit is moved to one position (Figs. 3 and 90 95 9), to overlie the abutment 37 on armature driving lever 36,--forming the abutment hereinbefore referred to. When the unit is moved to its other position (Fig. 2), the abutment 52 is carried out of overlying relation with lever 36, whereby lever 40 can be depressed without directly moving lever 36. Lever 41 has an integral abutment-forming projection 53, similar to member 52, which projection 53 always overlies the 100 stud 38, irrespective of which position the unit occupies.

The lever 40 is intermittently depressed by an eccentric 55 formed on a driving shaft 56 rotatably mounted in frame A. The eccentric 55 is encompassed by an anti-friction roll 57 which overlies and engages the abutment 52 on lever 40. When this abutment 52 also overlies the surface 37 of lever 36, as indicated in Fig. 4, a direct drive of the armature 25 from shaft 56 results. The drive spring 51 is not compressed, or at least not compressed to any substantial degree, and lever 36 is moved by the eccentric 55 in just the same manner as if this lever were directly engaged by the eccentric. When, however, the driving unit is shifted, by means to be described, so that abutment 52 is moved out of overlying relation with the surface 37 of lever 36, a quite different action 110 115 120 125 130 takes place. The eccentric depresses lever 40 and the latter moves toward lever 41, thereby compressing the drive spring 51. The latter, when fully stressed, is not, however, sufficient to overcome the force of magnetic attraction which holds the armature to its poles. Accordingly, the lever 41 which is engaged with stud 38 and thus moves only when the armature moves, remains stationary during the stressing of spring 51 and until

the projections 49 and 50 engage. The engagement of these projections permits an inelastic transmission from eccentric 55 through lever 40, projections 49 and 50, lever 41, stud 38, lever 36, and shaft 30 to armature 25, after the drive spring 51 has been stressed. This inelastic transmission of force serves to break the magnetic hold on armature 25 and move it a very short initial distance away from its poles. As soon as the magnetic hold is broken, the previously stressed drive spring 51 comes into play and moves the armature away from its poles at a speed independent of engine speed.

15 The driving unit may be shifted axially on shaft 30 from one to the other of its driving positions by any suitable means. As shown, a plate 58 is slidably mounted on the rear face of frame A (Figs. 7 and 8). A screw 59 and a pin 60, fixed to frame A, pass through slots in plate 58 and guide the same in its sliding movement. A lever 61, mounted to freely turn on screw 59 as a pivot, has cam surfaces 62 at its lower end which engage projections 63 on plate 58, whereby on swinging lever 61, plate 58 may be shifted. Plate 58 has a depending arm 64 which rides in groove 46 of the clutch collar, above described.

30 In the magneto described, the breaker points 20 and 22 separate, for the purpose of opening a normally short circuited primary winding, at an intermediate point in the flight of the armature away from its poles.

35 These breaker points will, therefore, close at a corresponding point in the return movement of the armature. Thus, the primary winding will be short circuited during the latter part of the return travel of the armature. This is desired to assist in securing a relatively quiet seating of the armature on its poles. The short circuited primary winding prevents a rapid building up of flux in the magnetic circuit, which would otherwise occur as the armature approaches its poles and which would tend to draw the armature into contact with its poles with a sharp noise. After the armature has been seated on its poles, all of the beneficial effect of the short circuited primary winding has been obtained and to continue this condition would be detrimental in that the desired building up of flux to a maximum intensity in the magnetic circuit would be unnecessarily delayed.

50 Therefore, means are provided to open the primary winding after the armature has been seated on its poles and to subsequently close this circuit before the armature again leaves its poles.

55 While the above object has been heretofore accomplished, as in the Brown and Clark U. S. Patent No. 1,489,382, dated April 8, 1924, I accomplish it in this magneto by a specifically different and improved mechanism which will now be described. Refer-

ring to Figs. 2 and 6, the second and lowest abutment 28 on the stem 23 of movable breaker point 22 lies directly beneath the forked end of a short lever 65, which is fixed to one end of a short shaft 66 rotatably mounted in a lug 67, depending from frame member 16. Fixed to the other end of shaft 66 is a lever 68, the free end of which is urged upwardly against a cam 69 by a spring 70, fixed to one of the bearing lugs 75 31. Cam 69 has two diametrically opposed projections 71 (Fig. 6) and is fixed to one end of a short shaft 72, rotatably mounted in a hub 73, depending from frame A. The other end of shaft 72 carries a gear 74 (Fig. 80 9) which is driven by a pinion 75 fixed to an extension 76 of the drive shaft 56. The shaft 72 is driven at one half the speed of shaft 56. Hence, as the armature is moved through one complete cycle on each revolution of shaft 56, it is necessary to provide the two projections 71 on cam 69. In Fig. 6, the parts are shown in the relative positions which prevail just after the armature has engaged its poles. With shaft 72 turning in a clockwise direction, it is apparent that one of the projections 71 will shortly depress lever 68 and thus shaft 66 and lever 65, whereby the breaker points 20 and 22 will be separated. Continued movement of shaft 72 will cause this projection 71 to ride off the end of lever 68, thereby allowing the breaker points to be reengaged by spring 26. The reengagement of the breaker points occurs just shortly before the armature 100 starts to leave its poles 13.

The operation of the magneto will sufficiently appear from the foregoing description and it is essentially like that of the magneto disclosed in Brown & Hendrickson Patent No. 1,517,948, dated December 2, 1924, except for the extra opening and closing of the breaker points, which has just been described.

110 The action of the armature driving mechanism, whereby the armature may be driven away from its poles either entirely by an inelastic transmission of force from the drive shaft or by an initial inelastic transmission of force followed by an elastic transmission of force from a previously stressed drive spring, is also broadly similar to that of the last named patent. However, the change from one form of drive to the other is effected by different means and in an approved manner. It is no longer effected by inserting a spacer (as between projections 49 and 50) to prevent the stressing of the drive spring and cause the armature to leave its poles at an earlier time than when stressing of the drive spring is permitted. Necessarily, such a spacer must be moving continually and is not convenient to operate. In the present case, the entire driving unit 120 shifted axially on its support by means of 130

the lever 61 and clutch groove 46, to effect the change in a most convenient manner. Also, such driving unit is of a simplified and improved character, especially from the manufacturing point of view. It consists simply of two punchings, pivoted together "scissors fashion" on a common hub having a clutch collar, and a drive spring. The two punchings are, or may be, exact 10 counterparts and can be produced in quantities at low cost. This driving unit not only presents important advantages from the manufacturer's joint of view, but it also has important advantages from the user's 15 point of view. It is not only more convenient to operate but it is sturdy and reliable in operation and compact in form.

The invention has been disclosed herein, in an embodiment at present preferred, for 20 illustrative purposes but the scope of the invention is defined by the appended claims rather than by the foregoing description.

What I claim is:

1. An armature driving mechanism for a 25 magneto, comprising in combination with a part connected to the armature for moving the same, an operating member capable of being bodily shifted into or out of position to engage said part, means for applying a 30 driving force to said operating member, whereby the latter will be moved and if positioned to engage said part will move the armature, a second operating member also adapted to engage said part, and elastic 35 means through which the first named operating member when shifted out of said position may transmit a driving force to the other operating member and thus to said part, whereby the armature may be driven 40 by an elastic transmission from said driving force when desired.

2. Armature driving mechanism for a 45 magneto, comprising, two relatively movable parts, resilient means associated therewith and stressed by their relative movement in one direction, means for applying a driving force to one of said parts to thereby stress 50 said resilient means and then move said other part, the latter transmitting the driving force to said armature, and means for bodily shifting said parts with their associated resilient means so that the first named part becomes effective to transmit an inelastic 55 driving force to the armature.

3. Armature driving mechanism for a 60 magneto, comprising, in combination with the armature and a part connected to move the same, two pivoted levers to one of which the driving force is applied and the other 65 of which is adapted to engage said part and transmit the force from the first named lever to the armature, resilient means associated with said levers and stressed by said transmission of force, and means for shifting one 70 of said levers so that the first named lever

may directly engage said part and effect an inelastic transmission of force to the armature.

4. Armature driving mechanism for a 75 magneto, comprising, an assembly consisting of two relatively movable levers with resilient means interposed between them, means for applying a driving force to one 80 of said levers which force stresses said resilient means and then moves the second lever, the latter adapted to transmit the force to the armature, and means for bodily shifting said assembly to cause the first named lever to transmit the driving force to the armature and render the first named 85 transmission ineffective to drive the armature.

5. Armature driving mechanism for a 90 magneto, comprising, two pivoted levers capable of relative swinging movement, resilient means associated with the levers and stressed by their relative movement in one 95 direction, means for applying a driving force to one of said levers which force stresses said resilient means and then moves the second lever, the latter adapted to transmit the force to the armature, and means for shifting one of said levers in a direction parallel to its pivotal axis to cause the first named lever to transmit the driving force to the armature and render the first named 100 transmission ineffective to drive the armature.

6. Armature driving mechanism for a 105 magneto, comprising two pivoted levers, elastic means tending to swing them apart, means for limiting the extent of such relative swinging movement, means for applying force to one of said levers in a direction such as to swing them toward each other and stress said elastic means, a part in the path of the other lever by means of which the armature may be moved, a second part by means of which the armature may be moved, and means for shifting said levers to bring the first named lever into the path of the second named part, whereby the armature may be moved without transmitting the driving force through the second lever.

7. Armature driving mechanism for a 115 magneto, comprising, two pivoted levers, elastic means tending to swing them apart, means for limiting the extent of such relative swinging movement, means for applying force to one of said levers in a direction such 120 as to swing them toward each other and stress said elastic means, a part in the path of the other lever by means of which the armature may be moved, a second part by means of which the armature may be moved, and means connecting said levers so that they may be shifted together axially with respect to the said pivot to bring the first named lever into the path of the second named part, whereby the armature may be 125 130

moved without transmitting the driving force through the second lever.

8. Armature driving mechanism for a magneto, comprising, two levers mounted upon a common pivot and shiftable axially thereon, elastic means tending to swing the levers apart, means for limiting the extent of such relative swinging movement, means for applying the armature driving force to one of said levers in a direction such as to tend to swing them together and stress said

elastic means, an armature driving abutment in the path of the other lever, a second armature driving abutment, and a lug on the first named lever adapted to engage the second armature driving abutment when said levers are shifted for the purpose of driving the armature without recourse to said elastic means. 15

In testimony whereof I have affixed my 20 signature.

PHELPS BROWN.
